TREILLAGE

Jacob G. Braun, Wilmette, Ill.

Application November 18, 1957, Serial No. 48,518

Term of patent 14 years

(Cl. D54—2)

fig. 1

Fig. 1 is a front elevation view of a trellage embodying my new design;

Fig. 2 is a fragmentary enlarged view of portions of the trellage shown in Fig. 1;

Fig. 3 is a sectional view taken along the line 3—3 looking in the direction of the arrows;

Fig. 4 is a sectional view taken along the line 4—4 looking in the direction of the arrows.

The characteristic feature of my design resides in the particular configuration of the artistry within the illustrated framework.

The back of the trellage shows merely the reverse side of the design as shown and is not repeated as unnecessary for a full disclosure of applicant's design invention.

I claim:

The ornamental design for a trellage, substantially as shown and described.
